UNITED STATES PATENT OFFICE

ALAN H. LEAMY, OF AUBURN, INDIANA, ASSIGNOR TO MANNING & CO., OF CHICAGO,
ILLINOIS, A CORPORATION OF ILLINOIS

DESIGN FOR AN AUTOMOBILE BODY

Application filed June 19, 1929. Serial No. 31,761. Term of patent 7 years.

To all whom it may concern:

Be it known that I, ALAN H. LEAMY, a citizen of the United States, and a resident of Auburn, county of De Kalb, and State of Indiana, have invented a new, original, and ornamental Design for an Automobile Body, of which the following is a specification, reference being had to the accompanying drawing, forming a part thereof.

In the drawings Fig. 1 is a perspective view and Fig. 2 is a rear elevational view of an automobile body showing my new design.

I claim:

The ornamental design for an automobile body substantially as shown.

ALAN H. LEAMY.
